UNITED STATES PATENT OFFICE

2,344,337

CORE WINDING MACHINE

Theodore L. Winestock, Lenox, Mass., assignor to
General Electric Company, a corporation of
New York

Application May 20, 1941, Serial No. 394,333

13 Claims. (Cl. 242—4)

My invention relates to strip coiling arrangements.

It is an object of my invention to provide improved methods and apparatus for rapidly coiling magnetic strip material tightly into non-circular coils of a predetermined size having spacers at predetermined portions of the coil, with means for feeding in spacers at the proper time and holding them in place until wound in, carrying out the operation with safety to the operator and requiring but negligible attention on the part of the operator.

The objects of my invention include also the provision of mechanical and pneumatic sheet material manipulating arrangements, arrangements for reducing variations in peripheral speed in non-circular coiling, arrangements for shutting down the apparatus in response to exhaustion of material to be fed or in case of emergency, and arrangements for adjusting the apparatus to accommodate strips or coils of different dimensions.

Other and further objects and advantages will become apparent as the description proceeds.

In a copending application of Jacob J. Vienneau, Serial No. 318,868, filed February 14, 1940, Electromagnetic induction apparatus and method of making the same, assigned to the same assignee as the present application, and which issued as Patent No. 2,305,649 on December 22, 1942, there is described a transformer or reactor having a core composed of magnetic strip material spirally wound flatwise to form a hollow non-circular cylinder. The cores specifically shown therein by way of illustration are elongated, either substantially elliptical or oblong, having spaces in the ends or short sides of the core, while close surface contact is maintained between adjacent layers of strip in the remaining portions of the turns of strip. The close surface contact is desirable for the sake of giving the core low magnetic reluctance in order to have low magnetizing current in the transformer. The spaces between layers of strip at a certain portion of the turn are provided to facilitate the assembly of the core with preformed and preinsulated form-wound conductive winding structures. As explained in the aforesaid Vienneau patent application, the spaces in the coiled core are obtained by winding spacers or pieces of sheet metal into the coil of strip when it is originally formed to the desired shape. Such an original coil of strip containing spacers is annealed in order to remove the mechanical strains introduced by the coiling process, and to restore the favorable mag-

netic properties of the material. After the coils of strip have been annealed they are applied to the conductive winding structure. This involves unwinding the strip and rewinding it around the 5 winding legs of the electrical or conductive winding structure. During the unwinding step the spacers drop out. Nevertheless, after the coil of strip has been rewound around the conductive winding leg, it has the same size and shape as when annealed, the respective turns have the same sizes and shapes as in the original coil of strip, and the portions of strip material are in the same consecutive order in the core of the completed electromagnetic induction apparatus 10 as in the original coil of strip as annealed.

One of the specific objects of my invention is to provide arrangements for rapidly and economically, as well as accurately, inserting the spacers in the coil of strip as it is being wound 15 on an arbor preparatory to being annealed.

A better understanding of the invention will be afforded by the following detailed description considered in connection with the accompanying drawings, and those features of the invention 20 which I believe to be novel and patentable will be pointed out in the claims appended hereto.

In the drawings Fig. 1 is a perspective view, partially schematic, of apparatus for coiling magnetic strip material into magnetic cores, which apparatus forms one embodiment of my invention; Fig. 2 is a fragmentary sectional view 25 of a guide for the magnetic strip material shown as cut by a vertical plane, with a fragmentary side view of the strip; Fig. 3 is a fragmentary sectional view of the strip guide shown as cut by a horizontal plane with a fragmentary top view of the strip; Fig. 4 is a detailed side view of a pneumatic spacer pick-up arm constituting a part of the apparatus of Fig. 1; Fig. 5 is a detailed top view of the apparatus of Fig. 4 shown 30 partially in section as cut by the plane 5, 5 of Fig. 4; Fig. 6 is a view of a broken section cut by the planes 6, 6 of Fig. 4 looking in the direction of the arrows; Fig. 7 is a front elevation 35 of an indexing mechanism at the front of the apparatus of Fig. 1, provided for controlling the insertion of spacers at proper intervals in the strip core as it is being coiled; Fig. 8 is a left side elevation, partially in section, of the mechanism of Fig. 7, seen as cut by the plane 8, 8 of Fig. 7 looking in the direction of the arrows; Fig. 9 is a fragmentary broken sectional view of 40 a linkage guiding cam slot arrangement constituting a part of the mechanism of Figs. 7 and 8 shown as cut by the planes 9, 9 of Fig. 7, and

as seen from above; Figs. 10 to 13, inclusive, are explanatory diagrams showing various stages in a cycle of operation of the apparatus of Fig. 1; Fig. 10 represents the stage of the operation with cams and other parts of the apparatus in the position illustrated in Fig. 1, at which stage a spacer is about to be placed against the strip; Fig. 11 represents the stage at which the spacer is placed against the strip; Fig. 12 represents the stage at which the spacer pick-up arm has dropped in order to pick up a spacer from a hopper containing the spacers; Fig. 13 represents the stage at which the hopper has been retracted to enable the spacer pick-up arm to pick up the top spacer in the stack contained by the hopper; Fig. 14 is a plan view of a coil of strip completely wound around a mandrel with spacers inserted at only one end or narrow side of the coil; Fig. 15 is a similar view with spacers inserted at both ends of the coil of strip; Fig. 16 is a perspective, partially exploded, view of an arrangement for quickly clamping the mandrel to the turntable of the coiling machine of Fig. 1 in an easily releasable manner; Fig. 17 is a perspective view of a fixture for bending the ends of the strip to shape before cutting off to facilitate the start of the next coil of strip, and Figs. 18 and 19 are diagrams illustrating the manner of using the fixture of Fig. 17. Like reference characters are used throughout the drawings to designate like parts.

In the machine illustrated in Fig. 1 there is a rotatable reel 11 carrying a relatively large supply or feed roll 12 consisting of strip material from which the strip 13 is unwound and wrapped into a coil 14 around a mandrel 15 secured to a turntable 16. A roller assembly 17 may be provided for rolling down any burrs which may have been caused by the slitting of wide sheet material to form the strip material contained in the roll 12. The burr-reducing roller assembly 17 is mounted between the supply reel 11 and the turntable 16. In the arrangement illustrated the supply reel 11 and the turntable 16 have vertical axes of rotation and are mounted above a horizontal platform or table 18 to which many of the other parts of the apparatus are secured. It will be understood, however, that my invention is not limited to the precise arrangement illustrated.

Mechanism is provided for inserting spacers at predetermined intervals between layers of the coil of strip 14 as it is being formed. In the arrangement illustrated spacers such as that shown at 19 are composed of sheet material having dimensions approximating the height and width of the end of the mandrel 15. For convenience the spacers 19 may consist of pieces cut from a strip of material similar to the strip 13. The spacer inserting mechanism is arranged to place the spacers, one at a time, against a portion of the inner surface of the strip 13 before that portion actually reaches the mandrel 15. The spacer-feeding mechanism includes a pick-up arm assembly 20 with a suction cup 21 for picking spacers from a stack 22 in a hopper 23. For holding the spacers, such as the spacer 19, against the surface of the strip 13 until they are wound into the coil 14 an electromagnet 24 is provided which magnetizes a length of the strip 13 between the roller assembly 17 and the mandrel 15.

For increasing the accuracy with which the spacers 19 are located in relation to the peripheral length of the strip 13, a hinged gate 25 is provided which normally rests against the inner surface of

the strip 13, near the mandrel 15, and which is provided with mechanism for releasing it at the proper instant to cause the spacer to be wound in accurately at the end of the coil 14. The gate 25 is controlled electrically and for opening it at the proper instant a cam switch arrangement 26, illustrated more in detail in Fig. 7, is provided. The timing of the operation of the cam switch arrangement 26 is corrected for the changing shape and angularity of the coil 14 as it builds up, by means of an indexing arrangement which will be described more in detail hereinafter.

The turntable 16, the gate timing mechanism 26, and the apparatus for operating the spacer-inserting mechanism including the pick-up arm 20 are all driven through suitable mechanical drives by a motor 27. In order to make the peripheral speed of the strip 13 more nearly uniform as it winds on to the non-circular coil 14, a pair of elliptical gears 28 and 29 is provided in the mechanical connection between the motor 27 and the turntable 16.

For controlling the application of power to the apparatus by the motor 27, a clutch 30 is provided having an operating foot pedal 31, to which is attached a spring 31', tending to hold the clutch out of engagement. For holding the foot pedal 31 in the clutch-engaging position, a spring-biased latch 32 is provided, having a normally open circuited solenoid 33 acting upon a plunger for releasing the clutch electrically when necessary. A source of electrical current 34 is provided for energizing the clutch releasing winding 33 when one of the switches to be described hereinafter is closed. For manually shutting down the apparatus by releasing the clutch there is a manual switch 35. For shutting down the apparatus when the coil 14 has been wound to the proper size, there is a counter 36 which closes a pair of contacts, not shown, when a predetermined number of turns for which the counter 36 is set have been wound on to the coil 14. In order to guard against producing a coil 14 having an insufficient number of spacers 19, a spacer-failure shutdown is provided including serially connected cam-operated contacts 37 and vacuum-failure operated contacts 38, which energize the clutch releasing winding 33 when both contacts 37 and 38 are closed.

To facilitate quickly securing the mandrel 15 to the turntable 16 and easily releasing it, the clamping arrangement illustrated in Fig. 16 is provided. To facilitate the cutting off of the strip after a coil has been completely formed and for suitably bending the end of the strip which will form the beginning end of the next coil, the bending fixture shown in Fig. 17 is provided.

To simplify the drawings and permit condensing the explanation, apparatus has been illustrated for winding only a single coil 14 and handling only a single strip 13. It will be understood, however, that my invention is not limited to this specific arrangement and that various parts, such as the reel 11, the turntable 16, and the spacer feeding mechanism, may be duplicated to provide for simultaneous coiling of identical strip cores under the control of a single gate-controlling switch and indexing arrangement 26 and a single counting arrangement 36 driven by a single motor 27.

The large rolls of strip material 12 are ordinarily received in that form from the mill, and it will be understood that it is advantageous to construct the reel 11 in such a manner that the top flange 39 may readily be removed, in order

that the roll 12 may be dropped over the center of the reel 11. For example, the flange 38 may be provided with button-hole slots to cooperate with the heads 39' of fastening screws. The reel center may, if desired, be in the form of an expanding mandrel, not shown, in order that the roll 12 will be tightly held on the reel 11. Suitable means are provided for maintaining constant tension of the strip unwound from the reel 11, such as means for supplying a fixed or automatically adjusted force restraining rotation of the roll 12. Such tensioning means may take the form of pneumatic or mechanical brake acting with automatically controlled force for maintaining the tension of the strip being unwound. Such a feed roll brake is represented schematically by a brake shoe 40 having a suitable lining 41 bearing on the roll 12. The brake shoe 40 is carried by a pivoted arm 42 which is connected to one end of a spring 43 secured at the other end to the table 18 in order to maintain a predetermined pressure between the brake shoe 40 and the roll 12.

The roller assembly 17 includes a pair of rollers 44 between which the strip 13 is drawn. The rollers 44 are mounted in a frame 45 which in turn is pivotally secured to a pivotally mounted bracket 46. The roller-carrying frame 45 includes a yoke mechanism 47 with rods bearing against journals of the rollers 44 in order to maintain a predetermined pressure between the rollers for rolling down any burrs or other irregularities which may exist in the strip 13. Suitable means for adjusting the pressure are provided such as nuts 48. For cleaning scale and other foreign matter from the surfaces of the rollers 44, wiping blades 49 and 50 are provided which are spring-pressed against the rollers 44.

The roller-carrying frame 45 has an extension 51 toward the supply reel 11 which has an opening shaped to receive the strip 13 and guide it between the rollers 44. The extension 51 (Figs. 1, 2, and 3) serves also to align the roller-carrying frame 45 at such an angle as to maintain the plane through the centers of the rollers 44 substantially perpendicular to the strip 13 as the angle of delivery of the strip 13 changes with reduction in size of the supply roll 12. For guiding the strip 13 vertically in the mouth of the extension 51 of the roller frame 45, inserts 52 (Figs. 2 and 3) near the mouth of the extension 51 are provided. In order to make the apparatus adjustable for strips of different widths, a plurality of slots 53 is provided in the extension 51 to receive the strip-guiding inserts 52. For varying the height at which the roller-frame 45 is supported, a suitable screw or rack arrangement operated by a crank 54 and carrying the bracket 46, may be provided. The bracket 46 is preferably mounted to have a horizontally pivoted axis in order to give full freedom to the strip 13 in maintaining its natural alignment in passing from the roll 12 to the coil 14.

The turntable 16 is carried by a vertical shaft suitably journaled in a bushing or bearing 55 secured to the table 18, and a bearing 56 formed in a lower horizontal plate or shelf 57. For reducing weight and cost the mandrels 15 are ordinarily made hollow and in order to provide a means for fastening the mandrels to the turntable 16 which means may be secured and released easily, the turntable 16 may be provided

with two vertical posts 58 and 59 secured thereto to cooperate with two openings 60 and 61 in the mandrels 15. For clamping the mandrel 15 to the turntable 16 over the posts 58 and 59, each of the posts 58 and 59 may be provided with projecting rods with overhanging or button-shaped heads 62 and 63 and a notched flat bar 64 may be provided with a threaded opening 65 to cooperate with a screw 66. The bar 64 has slots 67 and 68 adapted to fit under the heads 62 and 63 and the screw 66 has a handle 69 for rotating the screw 66 to drive the lower end 70 against the top of the bridging portion 15' of the mandrel 15 when the bar 64 is fitted under the screw heads 62 and 63. The apparatus is limited to handling mandrels of a particular size as the posts 58 and 59 may be provided with threaded holes 58' to facilitate bolting on fillers to increase the sizes of the posts to accommodate any desired size of mandrel.

The spacer feeding arrangement includes the sliding hopper 23 and the pivoted pick-up arm assembly 20 illustrated in Figs. 1 and 10 to 13. The hopper 23 is in the form of an inclined box with an open top. The box is slidably mounted on an inclined track in any suitable manner, for example, by means of rollers 71 rotatably secured to the hopper 23 and pairs of stationary rails 72 between which the rollers 71 and the sides of the hopper 23 are slidably held. The rails 72 are secured to the table 18 of the machine in a suitable manner, not illustrated. For controlling the movement of the sliding hopper 23 there is an arm 73 pivotally secured at the lower end to the hopper 23 and having a cam follower 74 at its upper end. A hopper retracting cam 75 is provided to cooperate with the cam follower 74. To hold the upper end of the arm 73 in place slidably, it may be formed with an elongated opening 76 through which a cam shaft 77 passes.

The pick-up arm assembly 20 is represented in Figs. 1 and 10 to 13 and illustrated more in detail in Figs. 4, 5, and 6. This assembly comprises an outer sleeve member 78 and a telescoping two part inner member consisting of an inner sleeve 79 and a projecting rod 80. The end of the rod 80 carries the suction cup 21 and has a passage 80' formed therein to which is secured a tubular member 81 for forming a connection between a pneumatic hose 82. The suction cup 21 is composed of a suitable resilient material such as soft vulcanized rubber, for example, and the hose 82 is likewise composed of a suitable flexible material which will withstand either vacuum or moderate air pressure. The sleeve member 78 of the spacer pick-up arm 20 is pivotally mounted at one end, which loosely surrounds a shaft 83 serving also as a second cam shaft. The outer sleeve member 78 has a slot 84, and an ear 85 secured to the inner sleeve member 79 projects through the slot 84. To the ear 85 is secured a cross-pin 86. A pair of springs 87 is connected between the pin 86 and the pivoted end of the outer sleeve member 78 for the purpose of resiliently biasing the inner sleeve member toward the pivot axis 83. The inner end of the rod 80 is made hollow and contains a compression spring 88 to permit the projecting end of the rod 80 to yield when the inner sleeve member 79 is pushed longitudinally forward in a manner which will be explained hereinafter. For limiting relative movement of the rod 80 and the inner sleeve member 79, the latter may be provided with a slot

88 which is closed at the forward end 90, and the rod 88 may have a transverse pin 91, secured therein, which projects into the slot 89 of the inner sleeve member 19 but does not engage the inner surface of the outer sleeve member 18.

For giving the spacer pick-up rod 88 both angular and longitudinal movement, two different cam arrangements are provided. The angular movement is provided by a lifting cam assembly consisting of a lifting cam 92 carried by the main cam shaft 11, a cam follower 93, and an arm 94 pivoted to the outer sleeve member 18. The outer sleeve member 18 has secured thereto a forked ear 95 pivotally holding one end of the arm 94 and the other end of the arm 94 is provided with an elongated opening 96 through which the cam shaft 11 passes. The cam 92 is so shaped as to lift the pick-up arm assembly including the rod 88 to the horizontal position for about 50 degrees of the angular rotation of the cam shaft 11 and to leave the pick-up arm assembly in the lower position represented by Figs. 12 and 13 during about 180° of the angular rotation of the cam shaft 11. The remainder of the angular rotation of the cam shaft 11 is consumed in the raising and lowering of pick-up arm.

The cam arrangement for producing the longitudinal motion of the rod 88 of the pick-up arm assembly consists of a cam 97 carried by the upper cam shaft 83 and a cam follower 98 in the form of a roller revolving on a pin 99 (Fig. 5) projecting laterally from the inner sleeve member 19 through a slot 100 in the far side of the outer tubular member 18. The transversely projecting pin 99 carries also a second roller 101 which is adapted to cooperate with a stationary rail 102 represented by dotted lines in Fig. 5 and omitted for simplicity from Fig. 1.

The rail 102 serves for limiting the upward movement of the pick-up arm assembly when the cam follower 98 is being pressed up by the cam 97.

The flexible hose 82 leading at one end to the suction cup 21 is connected at the other end to a T 103 (Figs. 10-13), which has one inlet connected to a suction valve 104 and a second inlet connected to an air pressure valve 105. The valves 104 and 105 are connected to a vacuum reservoir and an air pressure reservoir through a vacuum line 106 and a pressure line 107, respectively. The valves 104 and 105 are cam controlled having valve stems formed at their upper ends as cam followers 108 and 109 to cooperate with cams 110 and 111, respectively, carried by the main cam shaft 11. The cam 110 is so shaped as to open the vacuum valve 104 and apply suction to the suction cup 21 from the time a spacer has been picked up until it is in position to be placed against the strip 13. The air pressure cam 111 is so shaped as to apply air pressure to the suction cup 21 after the vacuum has been cut off in order to insure ejection of the spacer 19 from the suction cup 21, at once.

The magnet 24 for holding the spacer 19 against the inner surface of the strip 13, as the strip travels along to be wound upon the mandrel 15, has a pair of long pole pieces 112 and 113 of opposite polarity extending along the outside surfaces of the strip 13 near the upper and lower edges thereof (Fig. 1). The pole pieces 112 and 113 are of sufficient length to magnetize all of the portion of the strip material from a point slightly in back of the spacer feeding mechanism 20 to the mandrel 15. In order to obtain a strong

magnetomotive force from the magnet 24, it may be made in the form of an electromagnet having a coil 114 with an elongated opening surrounding a yoke 115 joining the pole pieces 112 and 113.

5 The pole pieces 112, 113 and the yoke 115 are composed of relatively permeable magnetic material. In order that the pole pieces 112 and 113 may continue to rest against the outer surface of the strip 13 while the non-circular mandrel 15 is being rotated, the magnet 24 is pivotally supported by means of a U-shaped bracket 116 pivoted coaxially with the point of tangency of the rollers 44 by means of pins 117 to suitable members such as the stationary bracket 118 supported by the table 18 of the apparatus. A spring 116' is provided for normally holding the electromagnet 24 toward the strip to supplement magnet pull. For holding the pivotal electromagnet 24 out of the way when the apparatus is being adjusted or a new coil of strip is being started, a latch 119 may be provided pivotally supported on a post 120 secured to the table 18. The electromagnet 115 is energized by a source of current, not shown, and normally remains energized throughout the cycle of operation of the apparatus.

The spacer gate 25 is pivotally secured to a bracket 121 attached to the swinging arm carrying the electromagnet 24. In the arrangement illustrated, the bracket 121 is formed to include a sleeve bearing 122 carrying a spindle 123. The lower end of the spindle 123 has an arm 124 secured thereto carrying the spacer gate 25, which extends transversely to the strip 13. The arm 124 or the spindle 123 may also carry a spring-pressed roller 125 adapted to bear resiliently against the strip 13 or the spacer 19 passing thereunder in order to hold the trapped spacer against the strip 13, thus preventing it from being plucked away by opening of the gate 25. To the upper end of the spindle 123 is secured a crank arm 126. For rotating the crank arm 126 to release a spacer by opening the gate 25, an electromagnetic plunger mechanism 127 is provided 45 consisting of a solenoid coil 128, a plunger 129, and a connecting rod 130 joined by wrist pins to the ends of the plunger 129 and the crank arm 126. The electromagnetic coil 128 for opening the gate 25 is electrically connected by means of 50 a pair of conductors 131 and contacts of the switch arrangement 26 to the current source 34.

The switch arrangement 26, as illustrated more in detail in Fig. 7, includes a rotating cam 132 carried by an extension of the main cam shaft 55 11. A micro-switch 133 having contacts, not shown, is operated by the cam 132. The contacts of the micro-switch 133 are connected in series with the conductors 131 to the current source 34. For varying the phase relationship between the 60 angular position of the cam shaft 11 and the instant of switch-closing operation, the micro-switch 133 is secured to a rotatable arm 134 and the angular position of the arm 134 is controlled by an indexing arrangement. This indexing arrangement is provided for varying the relationship between the angular position of the turntable 16 and the instant of opening of the gate 25, as the coil 14 increases in size, in order to allow for the fact that the peripheral lengths of the 65 turns of strip increase and the angle of approach of the strip changes as the size of the coil 14 increases. Since the angularity of the turns of strip varies from the inner layer to the outer layer of the coil 14, the indexing arrangement is so 70 constructed as to introduce an additional, not

necessarily non-linear, factor in order to keep the spacers in alignment as illustrated in Figs. 14 and 15.

The indexing arrangement comprises a disk 135 driven in the same direction as the cam 132 but at relatively low speed in proportion thereto and a linkage connecting the disk 135 to the switch-carrying arm 134. The disk 135 is connected to the cam shaft 77 through a set of changeable speed-changing gears 136 and a speed reduction gear box 137. A friction clutch 138 is also interposed for enabling the indexing arrangement to be reset after each coil has been completed. In order that any necessary deviation from linearity may be introduced in the speed relationship between the gear 135 and the cam shaft 77, the linkage between the disk 135 and the micro-switch carrying arm 134 is made adjustable in length. The linkage consists of a broken connecting arm constituted by two separate arms 139 and 140 joined by a pin 141. The arm 139 is pivotally connected to the disk 135 and the arm 140 is pivotally connected to a crank arm 142 secured to the micro-switch carrying arm 134. One of the connecting arms, for example the arm 139, may be formed with a bifurcated end to receive the end of the other arm 140. The pin 141 may be secured to one of the arms such as the arm 139 and is made of sufficient length to have a projecting end 143 forming a guide pin. For guiding the pin 143 and thus fixing the effective length of the linkage between the disk 135 and the crank arm 142, a plate 144 is provided having a slot 145 cut therein and adapted to receive the guide pin 143. The cam-slot plate 144 is removably secured to the supporting structure of the indexing arrangement in any suitable manner as by means of bolts 146. Different plates, such as the plate 144, are provided having cam slots of different shapes cut therein to provide for the coiling of strip cores having different shapes with different degrees of angularity. The arrangement is such that when a coil of strip is started on the mandrel 15, the guide pin 141 is at the upper end of the cam slot 145, as illustrated, and when the coil has been completed, the guide pin 141 has moved toward the lower end of the cam slot 145. In order to return the indexing arrangement to the starting position, a crank handle 147 may be provided to which it is connected by means of a spindle 148 and a pinion 149 meshing with teeth cut in a portion of the periphery of the disk 135. It will be understood that only a fraction of a revolution of the disk 135 is required.

The mechanical power for operating the apparatus is provided by the driving motor 27 which is connected to the driving side of the clutch 30 by means of a belt 150 in the apparatus illustrated in Fig. 1. The driving side of the clutch 30 is connected to a shaft 151 mounted in a gear box 152. Power is taken from the gear box 152 through an output shaft extending in two directions, or a pair of shafts 153 and 154 which extend from the gear box 152. The shaft 153 supplies power to rotate the turntable 16 and the shaft 154 indirectly drives the cam shafts.

The mechanical connection between the power shaft 153 and the turntable 16 includes the elliptical gears 28 and 29, one of which is connected to the shaft 153 and the other of which is connected to a shaft 155 which is in turn connected by pairs of bevel gears 156 and 157 to a vertical shaft 158 carrying the turntable 16. The elliptical gear 28 is so positioned angularly on its shaft 153 in

relation to the angular position of the turntable 16 as to reduce the angular speed of the turntable 16 relatively when the mandrel 15 is in the position with the greatest radius perpendicular to the strip 13 as illustrated in Fig. 1, and to increase the angular speed of the turntable 16 relatively when it is in the angular position perpendicular to the position shown, at which the radius is a minimum. In this manner the speed of travel of the strip 13 is made more nearly uniform, minimizing acceleration and deceleration of the heavy roll 12, and the tendency for the magnet 24 to slap the coil 14 as the mandrel 15 rotates from the short side to the long side, or vice versa, is minimized. I found that satisfactory results for this purpose may be obtained by utilizing gears 28 and 29 which are actually circular but which are eccentrically mounted on the shafts 153 and 155 respectively.

The power from the shaft 154 is communicated to the cam shaft 77 by means of a chain and sprocket arrangement 158. In order to permit changing the number of spacers inserted in the strip coil 14, that is to say, to permit changing the interval at which the spacers are inserted, I may provide a set of speed-changing gears 160 and a change speed gear shift lever 161. In the arrangement illustrated this consists of a pair of pinions 162 and 163 secured to the driving shaft 154 in such manner as to be rotatable therewith but longitudinally movable as by means of a spline 164. Cooperating with the pinions 162 and 163 are gears 165 and 166 secured to the driven shaft connected to the chain and sprocket arrangement 158.

In the arrangement illustrated the ratio between diameters of gears 162 and 165 is 1:2, and the ratio between the gears 163 and 166 is 1:3, so that the speed of the cam shaft 77 may be made either one-half or one-third that of the average speed of the turntable 16, since a 1:2 speed reduction is provided by the bevel gears 157. Accordingly, the arrangement as specifically illustrated provides for placing a spacer either once in each turn of the coil of strip 14, or once for each one and one-half turns of the turntable 16. Thus, the spacers will be placed either all at one end of the coil of strip or at both ends, according to whether the speed ratio between the shaft 154 (double the turntable speed) and the cam shaft 77 is an even integer or an odd integer. For the reasons explained in the aforesaid patent application of Jacob J. Vienneau, it is ordinarily desirable to place the spacers only at the ends or short sides of the rectangular mandrel 15. However, my invention is not limited to the specific arrangement illustrated and is not limited to the gear ratios shown which give the frequency of insertion of spacers represented by Figs. 14 and 15.

In the arrangement illustrated, the main cam shaft 77 and the upper cam shaft 83 are mechanically connected to rotate at the same speed and in the same direction by means of gears 167 and 168 connected to the shafts 77 and 83, respectively, and meshing with an idler gear 169.

As already explained, the upper cam shaft 83 drives the spacer placing cam 97. The lower cam shaft 77 drives the hopper retracting cam 75, the spacer pick-up arm lifting cam 92, the vacuum valve cam 110, the air pressure cam 111, and the gate-operating switch cam 134. This cam shaft also carries a cam 170 for periodically closing the contacts 37 of the spacer-failure shutdown circuit. In addition, an extension of the cam shaft

71 drives the indexing arrangement through the speed changing gears 136.

As already explained, the clutch-latch releasing solenoid 33 has a manual switch 35 for energizing it to disengage the clutch 30. The manual switch 35 is shown in conventional form for the sake of simplicity but is preferably in portable form of the type, which may be held in the hand and carried about, having flexible conductors 171 and 172 of considerable length for electrically connecting it to the wiring of the strip coiling apparatus. This permits the operator to observe the operation of the machine from any position and to shut it down in case of necessity regardless of his position at the time. It also facilitates the tending of several machines by a single operator, who carries all of the manual shut-down switches, such as the switch 35, with him as he moves about observing the operation of the various machines and starting new coils while the other machines are automatically winding coils of strip which have already been started. It is not necessary for the operator to shut down the machines when the machine in question has wound the desired number of turns on the coil of strip since this function is performed by the counter 36. The counter 36 is a device of a type well known to those skilled in the art which closes an electrical circuit after a predetermined number of turns has been counted and includes an adjusting arrangement for setting it for any desired number of turns to facilitate winding strip coils of different sizes.

As already explained, the apparatus includes an electrical circuit arrangement for shutting down the operation when there is a failure for any reason to pick up the spacer to be inserted in the coil. As stated, this includes the contacts 37 and 38 which connect the solenoid coil 33 to the current source 34 when both contacts 37 and 38 are closed. The contacts 37 are relatively movable under the control of an arm 173 adapted to be moved by the cam 170 which is so shaped as to close the contacts 37 while the vacuum valve operating cam 110 is in the latter part of its vacuum valve opening position and to open the contacts 37 again before the vacuum valve 104 has been closed. The contacts 38 are part of a vacuum switch including a bellows or diaphragm 174 which springs outwardly and closes the contacts 38 whenever there is a failure of maintenance of vacuum in the line 106 which would occur even though the vacuum valve 104 were open, if the suction cup 21 was also open to atmosphere by reason of having failed to pick up a spacer, which might occur in case the operator had overlooked placing a sufficient supply of spacers 22 in the hopper 23.

The bending fixture illustrated in Fig. 17 consists of a strip 176 having a bent end 177 conforming to the shape of the rounded corners of a nearly finished coil of strip and a flat end 178, to which is secured a block 179 which may be braced if desired by means of a rib 180 secured in any suitable manner as by welding to the strip end 178 and the block 179. If the strip 176 is not of the same width as the strip material 13, a centering piece 181 may also be secured to the strip 176. The parts 179 and 181 are of a length preferably equaling the width of the strip material 13 which is formed into the coils of strip 14. The block 179 has a beveled edge 182 with a sharpened corner 183 for bending the end portion of the strip material beyond the point of cut-off of the finished coil of strip.

The first operation of the operator after cutting the strip when a strip coil has been completed and after removing the completely wound coil of strip is to place a new mandrel over the posts 58 and 59 and to clamp it down by means of the screw 66 and its handle 69. Then the operator places the bent end 184 of the cut strip around one corner of the mandrel. The end has been bent by the fixture of Fig. 17, just before cutting the strip upon completion of the previously wound strip coil. The operator thereupon starts the apparatus by depressing the clutch pedal 31 and allows the turntable 16 to take on or two turns to hold the end of the strip in place. It will be understood, of course, that the operator has placed a sufficiently large stock of spacers 22 in the hopper 23 to permit winding a complete coil of strip 14. As the strip is fed from the roll 12 and passes through the mouth of the rear extension of the roller frame 45, it passes between the rollers 44 which roll down any burrs and overcome any irregularities in the flatness or thickness of the strip material 13. The wiping blades 49 and 50 keep the rollers 44 clean and thus prevent uneven stretching and extension of the steel, which would make impossible a rightly wound core. The strip then passes the pole pieces 112 and 113 of the spacer-holding electromagnet 24 and coils 30 around the mandrel 15, which is being rotated by the turntable 16. At proper intervals determined by the speed ratio between the drive shaft and the cam shafts, a spacer 19 is placed against the strip 13 and held in place by the magnetization of the magnet 24. Whenever the turntable 16 has reached the proper angular position the gate 25 opens to permit the spacer 19 to continue traveling and to be wound into the coil of strip 14 at one end or the other of the mandrel 15.

The sequential operation of the cams for producing a desired manipulation of the spacers is represented in Figs. 10 to 13. The direction of rotation of the cams is indicated by arrows. In Fig. 1 and in Fig. 10 the apparatus is shown in the position after a spacer has been picked up by the suction cup 21 and the spacer pick-up arm has been elevated to the horizontal position. As indicated by the arrows in Fig. 10, it will be observed that the cams are rotating in the counterclockwise direction and that the cam 92 has just reached the position at which the spacer pick-up rod 80 is lifted to its uppermost or horizontal position. The cam 92 is so shaped that the pick-up arm remains in this position for about 50 degrees of additional rotation and then drops abruptly.

The spacer placing cam 97, however, has a sharper lift and within a relatively few degrees of rotation projects the inner sleeve member 79 (Fig. 6), to the right, pushing the rod 80 also to the right and pushing the spacer 19 against the inner surface of the strip 13. This is represented by Fig. 11. The compression spring 68 is in the telescoping members and permits the rod 80 to yield so that the spacer 19 may be placed close against the strip 13 without any danger of damaging the mechanism. At this instant the air pressure cam 111 has opened, the pressure valve 105 admitting air under pressure to the hose 82 and to the suction cup 21 to make sure that the spacer 19 will be ejected from the cup 21 and will remain against the strip 13, under the force of the magnetization produced by the magnet 24. It will be observed that in

both Figs. 10 and 11 the vacuum valve cam 110 is in a position at which the vacuum valve is closed.

Further rotation of the cams permits the cam follower 98 to spring back, allowing the suction cup 21 to be retracted under the force of the tension spring 87. It also allows the cam follower 93 to drop, which permits the pick-up arm assembly to fall to the position represented in Fig. 12, and in which the suction cup 21 is directed toward the stack of spacers 22 in the hopper 23. It will be seen that at this time the vacuum valve cam 110 has reached the position opening the vacuum valve 104 so as to apply suction to the suction cup 21. Further rotation of the cams (Fig. 13) brings the hopper retracting cam 15 to the lifting portion of its periphery so as to retract the cam follower 74 and retract the hopper 23 against the suction cup 21 so that the top spacer in the stack 22 will adhere to the suction cup 21. As further rotation of the cams continues, the mechanism will approach the position represented by Fig. 10, and just before the position of Fig. 10 is reached, the vacuum is shut off so that the spacer 19 is held to the suction cup 21 merely by the suction retained therein. Shortly thereafter, as already explained, the position of Fig. 11 is reached and air pressure ejects the spacer from the suction cup 21. It is to be observed that the hopper retracted cam 15 has a lift of very short duration so that the hopper 23 falls back before the pick-up arm lifting cam 92 starts to raise the pick-up arm and the spacer 19 to the position shown in Fig. 10.

The phase relationship between the operation of the gate 25 and the cams has not been mentioned in connection with the operations thus far described represented by Figs. 10 to 13. Although this operation must have relationship to the angular positions of the other cams predetermined within quite wide limits, the actual angular relationship between the gate switch controlling cam 132 (Fig. 7) and the other cams depends upon the size of the mandrel 15 and the distance between the turntable and the gate 25. It will be understood, however, that the angular arrangement between the gate switch controlling cam 132 and the spacer pick-up operating cams must be such that the spacer 19 is placed against the strip 13 before the gate 25 is opened by the micro-switch 133 and the time interval between the placing of the spacer 19 against the strip 13 and the opening of the gate 25 must be at least as long as the time required for the strip 13 to travel from the position opposite the spacer pick-up arm to the position opposite the gate 25. This time interval may actually be considerably longer because the gate 19 holds the spacers in place until the proper time to release the spacer. This time interval must in any event be great enough to allow for the slight variations in timing of the operation of the gate 25 produced by the indexing arrangement described in connection with the switch 26.

As the coiling of the strip progresses, the guide pin 141 (Fig. 7) gradually moves down in the cam slot 145 but when the coiling of the strip has been completed the guide pin 141 reaches a lower position. Before starting another coil of strip the operator manipulates the crank handle 147 to bring the guide pin 141 back to its original position. It will be observed that as the guide pin 141 moves lower in the cam slot 145,

the lag of the micro-switch carrying arm 134 is progressively increased so that with each revolution of the gate switch controlling cam 132, the switch is closed slightly later and the gate opens slightly later with relation to the angular position of the turntable 16 to allow for increasing perimeter of the turns of strip in the coil. The cam slot 145 serves to correct for the decreasing sharpness of the bends in the strip at the corners of the mandrel. Lack of linearity in the required change is taken care of by the shape of the cam slot 145.

Ordinarily the switch 36 is set to operate slightly before the complete number of turns of strip have been wound on the coil 14. After the operation of the apparatus has been shut down by the closure of the counter switch 36, the operator completes the winding of the coil or strip by depressing the clutch pedal 31 to reach the coil around and just before reaching the last turn of strip the operator places the bending fixture of Fig. 17 on the coil of strip 14 (as at Fig. 18), soon winding in the curved end 177 of the bending fixture. After the strip has been wound over the sharp edge 183 of the bending fixture to form a sharp bend 184, the operator releases the clutch pedal 31 to stop the machine and the bending fixture forms a bight 185 (Fig. 19) which enables the operator to cut the strip at the point 186 by means of a pair of shears. The flat end of the strip on the coil is then clamped down manually and may if desired be tack welded to the underlying layers of strip. The mandrel is then released by loosening the clamping screw 68 of Fig. 16 and the apparatus is ready for substitution of another mandrel. Before the apparatus is started again, however, the hand crank 147 of the indexing arrangement is rotated to bring the guide pin 141 to the initial uppermost position in the cam slot 145.

In accordance with the provisions of the patent statutes I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. A coil winding machine comprising a rotatively driven turntable, a mandrel removably secured thereto, a supply roll for feeding strip material to the mandrel as it is rotated, mechanism for intermittently placing spacers against the inner surface of the strip material before it reaches the mandrel and an electromagnet having pole pieces in proximity to the strip material for magnetizing it and holding the spacers against the inner surface of the strip material until the spacers are wound into the coil of strip around the mandrel.

2. A coil winding machine comprising a rotatable member around which a coil of strip is to be wound, means for supplying strip material to form such a coil around the rotatable member, and a mechanism for intermittently placing spacers against the inner surface of the strip material for causing such spacers to be wound into the coil of strip being formed.

3. Apparatus for winding strip material into a coil comprising a mandrel, means for rotating it, means for supplying strip material to a coil being wrapped around the mandrel, mechanism for in-

intermittently feeding spacers against the inner surface of the strip before it is wound on to the coil, means for temporarily holding such spacers to prevent their being wound into the coil, an electrically controlled means for releasing such spacers at predetermined intervals, said electrically controlled means including a switch with relatively rotatable elements one of which is driven in synchronism with the mandrel, and the other of which is carried by an arm adjustable in angular position, said arm having means for gradually changing its angular position throughout a fraction of the revolution in the course of winding a completed coil of strip.

4. Apparatus of the type set forth in claim 3 including an index plate, and a guide pin cooperating therewith connected to the mechanism for varying the angular position of the arm of the electrical spacer releasing device, said index plate being shaped for varying the proportional relationship between angular movement of said arm and rotation of the mandrel in accordance with a predetermined curve to correct for variations in angularity of the coil of strip being wound.

5. Apparatus for winding a coil of strip comprising a member for receiving strip material to be coiled, means for rotatably driving said member, means for feeding strip material thereto and a feeding mechanism for placing spacers against the inner surface of the strip material intermittently in order to be wound into the coil of strip being formed, said spacer-feeding mechanism comprising a hopper for containing a supply of spacers, a pivoted arm with a suction cup at the end thereof, mechanism driven synchronously with the aforesaid rotatable driving mechanism for alternately deflecting said arm toward the hopper and toward the strip of material which is passing into the coil being formed and for momentarily producing relative movement in the approaching direction between said hopper and said suction cup when the arm is in the first of said alternate deflected positions and then between said suction cup and the strip when the spacer feed arm is in the second of its alternate deflected positions, means for applying a vacuum when said suction cup is in proximity to the spacer hopper, and means for releasing said vacuum when the suction cup carrying the spacer is in proximity to the strip of material passing into the coil.

6. Apparatus for winding strip material into a coil comprising a member for receiving strip material to be formed into a coil, means for rotating said member, means for supplying strip material to said rotating member, mechanism for intermittently placing spacers against the inner surface of the strip material before it reaches the coil of strip, means for temporarily holding said spacers, and means for releasing them at predetermined intervals.

7. In a machine for assembling separate pieces with a structure being formed and intermittently feeding and placing said pieces, pneumatic piece-handling apparatus comprising a movable member including a suction cup, a hopper for containing pieces to be handled, a mechanism for intermittently bringing the suction cup and the uppermost piece in the hopper in contact for picking up one of said pieces and mechanism for moving the suction cup into position for assembling such a piece with the structure being formed, a source of driving power connected to the aforesaid mechanism with means for disconnecting said power, a suction or vacuum line,

means for connecting said vacuum line to the suction cup when the suction cup and hopper are in proximity, said power disconnecting means comprising a pair of serially connected switches

5 arranged to disconnect power by operation of both switches, means for temporarily operating one of said switches after the vacuum line has been connected to said suction cup for picking up a piece, the other of said switches being a 10 vacuum switch connected to said vacuum line and arranged to operate in response to failure of vacuum whereby failure of said suction cup to pick up a piece to be assembled results in lack 15 of vacuum at the vacuum switch at the time when the first-mentioned switch is operated and whereby the circuit to the power disconnecting means is operated and power is shut down to prevent further operation of the apparatus until failure of the supply of pieces to be picked up 20 is corrected.

8. Apparatus for winding magnetic strip material into an elongated coil of strip comprising an elongated mandrel, means for rotating the mandrel to wrap strip material around it, means 25 for supplying strip material to the coil being wrapped around the mandrel, said means for rotating the mandrel comprising a source of mechanical power having a substantially uniform speed of rotation and having a pair of elliptical gears interposed between it and the mandrel in order to vary the instantaneous speed of angular rotation of the mandrel to minimize the variations in peripheral speed of the strip being 30 coiled on the mandrel.

9. In apparatus for assembling separate pieces with a structure being formed and placing such pieces at intervals, a movable pick-up arm carrying at the end thereof a suction cup adapted to be brought into contact with a piece to be 35 picked up, mechanism for moving said arm back and forth between a pick-up position and an assembling position, a hopper for pieces to be picked up in proximity to said pick-up position, mechanism for applying suction to said suction 40 cup when the cup is in the pick-up position and for cutting off said suction and applying air pressure when the cup is in the assembling position, and means for temporarily and successively holding the separate pieces in assembly with the 45 structure at the desired intervals until the pieces are tightly bound in the structure.

10. Apparatus for winding strip material into a coil comprising a mandrel, means for rotating it, means for supplying strip material to a coil 50 being wrapped around the mandrel, mechanism for intermittently feeding spacers against the inner surface of the strip before it is wound on to the coil, including means for correlating the timing of the spacer feed to the angular position of the mandrel having means for progressively varying said correlation.

11. Apparatus such as set forth in claim 10 including an indexing mechanism for controlling the rate of variation in the correlation between 55 the timing of the spacer feed and the mandrel rotation, said indexing mechanism having a cam or index surface cut with a curved shape to produce a predetermined change in the variations in spaced feeding time and coil rotation to correct for variations in angularity of the coil of strip being wound.

12. A coil winding machine comprising a rotatable member around which a coil of strip is to be wound, means for supplying strip material 75 to form such a coil around the rotatable member.

a mechanism for intermittently placing spacers against the inner surface of the strip material for causing such spacers to be wound into the coil of strip being formed, and magnetomotive force producing means for magnetically attracting said spacers against the inner surface of the strip material to hold them in place until wound into the said coil of strip.

13. A coil winding machine comprising a member for receiving strip material to be coiled, means for rotatably driving said member, means for supplying strip material to form a

coil around the rotatably driven member, mechanism driven synchronously with said first-mentioned driving means for intermittently placing spacers against the inner surface of the strip material to cause such spacers to be wound into the coil of strip being formed, and means for changing the proportional relationship between the rate at which the feeding mechanism is driven and the rate at which the first-mentioned

5 10 rotatable member is driven.

THEODORE L. WINESTOCK.
